(57) **CLAIM**

The ornamental design for a myofascial tool, as shown and described.

DESCRIPTION

FIG. 1 is a top, front, left perspective view of a myofascial tool showing my new design;

FIG. 2 is a left side view thereof;

FIG. 3 is a right side view thereof;

FIG. 4 is a top view thereof;

FIG. 5 is a bottom view thereof; and,

FIG. 6 is a top, rear, left perspective view thereof, showing my new design of FIGS. 1-5 in an exemplary environment. The uneven-length broken lines immediately adjacent to the shaded area define the bounds of the claimed design and form no part thereof. The even-length broken lines depicting the remainder of the myofascial tool form no part of the claimed design. The broken lines depicting exemplary environment in FIG. 6 form no part of the claimed design.
